UNITED STATES PATENT OFFICE.

ANDREW FRANCIS NEY, OF EAST KEW, VICTORIA, AUSTRALIA.

MACHINE FOR LEVELING AND STACKING MATCH-SPLENTS.

1,299,995.

Specification of Letters Patent. Patented Apr. 8, 1919.

Application filed January 28, 1919. Serial No. 273,614.

To all whom it may concern:

Be it known that I, ANDREW FRANCIS NEY, a subject of the King of Great Britain, residing at "Glenelg," Edward street, East 5 Kew, in the State of Victoria, Australia, have invented certain new and useful Improvements in Machines for Leveling and Stacking Match-Splints, of which the following is a specification.

10 This invention consists of a machine for leveling match splints and stacking same uniformly into blocks ready to be fed into the match making machines.

The machines heretofore employed for 15 this purpose consisted of a comparatively shallow reciprocating receptacle down into which was swung a hinged hopper having a partitioned bottom to separate the stacks of splints. When the receptacle was filled 20 the hopper was swung up leaving the splints in unsupported stacks which had to be removed by hand and placed in trays or boxes to be subsequently carried to the match making machines.

25 The lifting of the hopper and the manual handling of the splints occasions disarrangement of the stacks and inevitable wastage and the object of this invention is to produce a machine which will obviate manual handling of the stacks and deliver same into boxes containing quantities as required for feeding the match making machines.

Accordingly the receptacle is provided 30 with a slide bottom or tray upon which is placed a number of narrow deep boxes having vertically movable loose bottoms supported by uprights on a vertically operated skeleton frame or deck. A detachable hopper with a partitioned bottom is fitted on 35 the receptacle and as the splints delivered into the hopper are shaken into the boxes the bottoms of same, which at the commencement of operation are near the top, gradually descend until the boxes are filled 40 when an end door of the machine is opened and the bottom tray of the receptacle supporting the boxes is withdrawn and taken to the match making machines where the boxes are inverted and compact blocks of

uniformly level splints are delivered into 50 the hopper of the machine.

The drawings illustrating the invention comprise:

Figure 1 a plan of the machine (broken) and showing a horizontal section of some 55 boxes taken below the bottoms thereof.

Fig. 2 a part longitudinal vertical section through some boxes shown containing splints.

Fig. 3 is a transverse section on line III— 60 III of Fig. 1.

Fig. 4 is a plan of the gearing beneath the receptacle.

Fig. 5 is a detail view of said figure on 65 line V—V thereof; and

Fig. 6 is a side view of portions of the gearing shown in Figs. 1 and 4.

Referring to these drawings the receptacle 1 is formed with a slide bottom or tray 2 provided with a handle 3 and supported on angle iron runners 4 on the bottom of the sides of the receptacle. At one end of the receptacle is a removable door 5 provided with a handle 6 and secured by clamps 7.

75 The frame of the receptacle is supported upon rocker arms 17 mounted on pivots 18 on the frame F of the machine and reciprocating motion is imparted to the receptacle by means of eccentrics 19 the rods 20 of 80 85 which are connected to pins 60 on the rear frames of the receptacle.

The hopper 8 fits into the top of the receptacle and is shouldered to be seated on the top edge thereof as in Fig. 3. The bottom of the hopper is formed of transverse partition bars 9 and longitudinal metal partition plates 10 forming rectangular divisions.

Upon the tray 2 are packed a number of 90 deep narrow boxes 11 which fill the receptacle, the adjacent side edges of said boxes being covered by the bars 9 as in Fig. 2. The bottoms 12 of the boxes are loose and are supported upon uprights 13 of metal for 95 instance, which uprights preferably arranged in pairs for each box extend upwardly from a skeleton frame or deck 14

and pass through guide slots 15 formed in longitudinal horizontal bars 16 fixed at their ends to the frame of the receptacle and also pass through the slots 66 formed in the 5 slide tray 2.

The frame 14 is provided with grooved slide blocks 21 each so interengaged with the upper end 22 of a vertical movable rack 23 as in Fig. 3 as to reciprocate with the 10 motion of the receptacle and at the same time travel vertically with the rack. In order to guide the frame 14 it engages at its corners with vertical angle iron guides 63 fixed to the frame of the receptacle and 15 extending vertically downward therefrom. The racks 23 slidably engage vertical grooved guides 24 and are operated by pinions 25 each mounted on a longitudinal shaft 26 provided with a worm wheel 27 gearing 20 with a worm 28 on a transverse shaft 29 provided with a clutch 30.

Upon shaft 29 is mounted a ratchet or disk 31 operated by a pawl 32 on a connecting arm 33 pivoted on a lever 51 Fig. 6 25 connected by a link 52 with the crank pin 34 of a crank disk 35 on a transverse shaft 36 rotated by means of a sprocket gearing 37 deriving motion from the main shaft 38 upon which the eccentrics 19 are mounted. 30 The rate at which the racks and consequently the bottoms of the boxes will be lowered may be regulated by adjusting the arm 33 relative to the pivots 53 of the lever. This may be effected by connecting the 35 arm 33 to a block 54 vertically movable on a screw threaded rod 55 rotated by a nut 56 by means of a finger grip 57 as in Fig. 6. By this means the pawl 32 in its idle stroke will pass over one or more teeth of the 40 ratchet wheel or disk 31.

By means of this gearing or similar gear for the same purpose the racks 23 and consequently the bottoms 12 of the boxes supported by the uprights 13 are gradually 45 lowered as said boxes are filling with the splints.

The clutch 30 can be operated manually by means of a lever 39 connected by a link 40 with a bell crank lever 41 provided with 50 a connecting rod 42 attached to a hand operated lever 43.

Means are also provided for automatically throwing the clutch out of gear when the boxes are nearly filled and for this purpose a trip finger 44 is fixed to the shaft 26 adjacent this gear so as to contact at a predetermined time with the projecting end 45 of the bell crank lever 40 and accomplish the same object as the hand lever 43 60 when operated to declutch the gear.

In order to maintain the clutch in one or other of its positions, the bell crank lever 41 is connected by a rod 46 with a vertically disposed arm 47 mounted on a pivot 48 on

a ground block and provided at the top with 65 a weight 49. This weighted arm comes to rest on one side or other of the central vertical line of the pivot and prevents inadvertent reversal of the clutch.

The racks must be raised at the start of 70 operations to carry the bottoms of the boxes to the top as in Fig. 3 and this may be accomplished by gearing but according to the construction illustrated the shaft 29 is provided with a crank hand wheel 50 75 which is operated when the shaft is de-clutched to reverse the worm gearing, the shafts 26 and pinions 25 which raise the racks or to complete the final descending motion of the racks.

With this machine as illustrated the automatic throw out of the clutch takes place when the boxes are not quite filled and the divisions of the hopper are filled with splints. To finally complete the descent of 85 the bottoms of the boxes and completely fill the latter, the hand-wheel 50 is operated and also for the purpose of insuring the upright supports 13 being withdrawn from the slots 66 in the tray 2. 90

I claim:—

1. In a machine for leveling and stacking match splints, a reciprocating receptacle, a plurality of boxes in said receptacle, a loose normally raised vertically movable 95 bottom in each box, means to lower said bottoms as the boxes fill with splints, a hopper detachably mounted in the top of the receptacle, a partitioned bottom in the hopper, a slide tray in the bottom of the 100 receptacle to support the boxes and vertically movable uprights to support the loose bottoms of the boxes.

2. In a machine as set forth in claim 1, a vertically movable frame to which the uprights supporting the box bottoms are fixed, 105 adapted to reciprocate with the receptacle.

3. The construction as set forth in claim 2, and in which the receptacle is provided with downwardly extending guides with 110 which engage the corners of the vertically movable frame.

4. The construction as set forth in claim 2 and in which the frame is provided with slide blocks interengaging with the means 115 employed for the vertical movement of the said frame.

5. The construction as set forth in claim 4, and in which the slide blocks engage with the upper ends of racks working in vertical 120 guides and operated by pinions rotated by gearing.

6. The construction as set forth in claim 2 and in which the uprights pass through slotted guide bars and through slots in a 125 slide tray forming the bottom of the receptacle.

7. The construction as set forth in claim

5 and in which a rotating finger on a shaft of the gear contacts with a bell crank lever which operates a clutch in the gearing for the purpose specified.

5 8. The construction as set forth in claim 5 and in which the pinions are mounted on shafts rotated by worm gearing through the medium of a shaft operated by pawl and ratchet gearing.

9. The construction as set forth in claims 10 7 and 8 and in which the clutch is on the shaft operating the worm gearing and said shaft is provided with a hand wheel.

10. The construction as set forth in claim 7 and in which the bell crank lever operating the clutch is connected by a connecting rod with a hand lever.

ANDREW FRANCIS NEY.
